CLAIM

The ornamental design for a cigar cutter, as shown and described.

DESCRIPTION

FIG. 1 is a left side elevation view of a cigar cutter embodying my new design;

FIG. 2 is the rear elevation view thereof;

FIG. 3 is a front elevation view thereof;

FIG. 4 is a top plan view thereof; and,

FIG. 5 is a right side elevation view thereof.

The bottom plan view is a mirror image of FIG. 4 with the exception of the opening along the top of the rear panel.
